UNITED STATES PATENT OFFICE.

ALBERT ARTHUR ALLEN, OF ORTONVILLE, MINNESOTA.

DRAFTING INSTRUMENT.

No. 819,495.

Specification of Letters Patent.

Patented May 1, 1906.

Original application filed July 7, 1904, Serial No. 215,622. Divided and this application filed April 8, 1905. Serial No. 254,431.

To all whom it may concern:

Be it known that I, ALBERT ARTHUR ALLEN, a citizen of the United States, and a resident of Ortonville, in the county of Big Stone and State of Minnesota, have invented a new and Improved Drafting Instrument, of which the following is a full, clear, and exact description, this being a division of the application for Letters Patent of the United States, 10 Serial No. 215,622, filed by me July 7, 1904.

The object of the invention is to provide a new and improved drafting instrument, more especially designed for the use of tanners, plumbers, and other mechanics in laying out 15 the blanks for forming elbows, T's, and other articles of sheet metal and like material.

The invention consists of novel features and parts and combinations of the same, as will be more fully described hereinafter and 20 then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a sectional plan view of the same on the line 2 2 of Fig. 1, and Fig. 3 is a transverse section of the same on the line 3 3 of Fig. 1.

The divider A (shown in the accompanying drawings) is arranged for obtaining on the diameter of a tubular body unequally-spaced-diametrical ordinate points. This divider 35 may be used in connection with a peripheral divider of any suitable or improved construction—such, for instance, as shown and described in the Letters Patent above referred to and arranged for obtaining ordinate 40 points spaced equal distances apart and dividing the periphery of a tubular body into equal parts. By drawing from these points it is evident that curved coördinates are obtained to permit of conveniently and quickly 45 drawing the desired curve.

The divider A is constructed in detail as follows: A plurality of spacing-bars C, C', C'', and C''' are arranged parallel to each other, the bars C' and C being the end bars, the bar 50 C''' the middle bar, and the bars C the intermediate bars, which latter and the middle bar C''' are mounted to slide in bearings D, pivotally connected with the outer ends of 55 links or lazy-tongs E, carrying at the middle of some of the links bearings F, mounted to slide on a cross-rod G. The middle spacing-

bar C''' is secured at H' to the rod G, while the intermediate bars C have bearings H slidably engaging the rod G. The end links or lazy-tongs E are connected by pivots I and I' with bearings H² and H³, slidably engaging the rod G and rigidly carrying the end spacing-bars C' and C''. The pivots I and I' are in the form of clamping-screws to allow the operator to screw up the ends thereof and 60 clamp the fixed parts in position to hold the divider against movement after the desired adjustment of the parts is made, as herein-after more fully described.

The links or lazy-tongs E are graduated in 70 size—that is, they gradually increase in size from the ends toward the middle, as plainly indicated in Fig. 1—the links being so graduated in size that the spacing-bars C, C', and C'' stand in such relation to each other that 75 they produce diametrical ordinate points. By adjusting the lazy-tongs E so that the points of the end spacing-bars C' and C'' are a distance apart corresponding to the diameter of the tubular body the spacing-bars C and 80 C''' located between the end spacing-bars C' and C'' are spaced unequal distances from each other, and the points marked on the diameter corresponding to the said intermediate spacing-bars are diametrical ordinate 85 points. It is understood that lines drawn through the ordinate points at right angles to the diameter divide the circumference of the circle for the said diameter into equal spaces.

By reference to Figs. 1 and 3 it will be seen 90 that the spacing-bars C, C', C'', and C''' are extended beyond the bearings D to form extensions C⁴, which are bent inwardly toward the extension C⁵ of the middle spacing-bar C''' it being, however, understood that the said extensions are so bent that the distance between the points at the extension ends will be less than the distance between the points at the other ends of the bars to permit of using the extensions for small diameters the 95 same as the other ends of the spacing-bars, which are used for large diameters.

In order to lay out the blanks for an elbow, for instance, the operator opens the lazy-tongs E so that the distance between the end 100 spacing-bars C' and C'' corresponds to the diameter of the tubular body, and then the operator marks the diametrical ordinate points on the blank sheet of tin or other sheet metal, these points corresponding to the intermediate spacing-bars. The operator now figures 105 out the length of the periphery of the tubu-

lar body and extends the same at right angles to the diameter laid out on the sheet between the end spacing-bars C' and C^2 , as above explained, and then by means of a suitable peripheral divider arranged for obtaining ordinate points spaced equal distance apart the operator divides the periphery of the tubular body into equal parts and marks the peripheral points on the sheet. The co-
ordinate lines are then drawn from both the diametrical and peripheral points, the point of intersection of the said lines giving the curve coördinate for forming the necessary curve. The operator now cuts along the line of this curve and then bends the two pieces of the blank into a tubular shape, so that the two pieces peripherally fit at the miter-joint along the curved edges, as will be readily understood.
For forming T's and other articles the operator proceeds in substantially the same manner as above described.

It is understood that the instrument can be readily employed in laying out various other curves required in the formation of tubular jointed bodies.

By the use of the device the mechanic needs no patterns to be guided by; but he can quickly set the divider A to a given diameter for the purpose above described.

Having thus described my invention, I

claim as new and desire to secure by Letters Patent—

1. An instrument for obtaining curved co-ordinates, comprising a diameter - divider having spacing-bars, a cross-bar mounted to slide in bearings on the said spacing-bars, and connected links slidably connected with the said spacing-bars and the said cross-bar.

2. An instrument for obtaining curved co-ordinates, comprising: a diameter - divider having spacing-bars, a cross-bar mounted to slide in bearings on the said spacing-bars, connected links slidably connected with the said spacing-bars and the said cross-bar, and a fastening device for holding the parts against movement.

3. An instrument for obtaining curved co-ordinates, comprising a diameter - divider having spacing-bars arranged parallel and having reducing extensions at one end, a cross-bar mounted to slide in bearings on the said spacing-bars, and connected links slidably connected with the said spacing-bars and the said cross-bar.

In testimony whereof I have signed my name to this specification in the presence of two subscribing witnesses.

ALBERT ARTHUR ALLEN.
